UNITED STATES PATENT OFFICE.

SAMUEL S. WATERS, OF WASHINGTON, DISTRICT OF COLUMBIA, ASSIGNOR TO AEOLIAN COMPANY, OF NEW YORK, N. Y., A CORPORATION OF CONNECTICUT.

METHOD OF MAKING RECORDS FOR MUSICAL INSTRUMENTS.

1,122,826.

Specification of Letters Patent.

Patented Dec. 29, 1914.

Application filed June 27, 1910. Serial No. 569,088.

To all whom it may concern:

Be it known that I, SAMUEL S. WATERS, a citizen of the United States, residing at Washington, in the District of Columbia, have invented new and useful Improvements in Methods of Making Records for Musical Instruments, of which the following is a specification.

My invention consists of a method of 10 making the records of musical instruments to be played in accompaniment with each other, and particularly to the making of phonograph and piano records adapted to be played in accompaniment. While of the 15 particular relation and adaptation stated, however, my invention is capable of use in connection with other instruments, and in other situations in part or as a whole, its advantages being realized in part or as a 20 whole depending upon the manner in which it is used.

It has been proposed to play phonographs and pianos in synchronism in accompaniment with each other. A number of difficulties are found to be present when this is attempted, the chief among which is a variance in musical time of the records of the phonograph and the piano. This is due for the most part to the fact that these records 30 have not been properly made, or have not been made for use in the instruments which are to reproduce them in accompaniment. In order that the best results be secured in playing records of two instruments in 35 accompaniment, the records should be especially made for this purpose. Otherwise not only will there be slight variance in musical time due to variance in speed of the record elements used and to imperfections in the 40 records themselves, but there will also be a variance due to the fact that the linear dimensions of the records will not bear such a relation to each other that their movement in the respective instruments can be adjusted 45 to cause them to play in any sort of musical time whatsoever.

When phonograph records are prepared simultaneously with piano records by simultaneously acting on the producing devices, 50 the piano sounds, if of the prominence which they should be, impress themselves upon the phonograph element with a resulting impairment of the tone of the voice or other sound record being made on the phonograph record element. This should be avoided in

all instances if possible, and especially should it be avoided when the phonograph record being made is that of a voice, or when the phonograph record is to be a predominating record of a voice, or of a musical 60 instrument, or of some other sound.

It is the object of my invention to avoid this difficulty and to produce sound records which shall be pure in tone, and records which when played in accompaniment will 65 give results most closely approaching those attained in the personal performances of professionals.

Upon an understanding of my invention, it will be evident that I have not only 70 accomplished the objects of my invention, but have developed a method possessing most important advantages along other lines, chief among which may be mentioned the fact that by my invention I may produce 75 piano records for use in accompaniment with phonograph records already made.

According to the method of my invention, I first make the predominating or phonograph record by operating on a suitable 80 record element in any of the known ways, and thereafter produce the piano record by reproducing the phonograph record and accompanying the same with operation on a device adapted to make the piano record on 85 a blank record element, driving the blank record element at a speed absolutely proportional at all times to the speed of the first record being reproduced and suited to the requirements of the instrument in which it 90 is to be used.

In the drawings I show diagrammatically an apparatus arranged for the carrying out of my invention.

Referring to the drawings, 10 is the record 95 sheet moving mechanism of an automatic player piano or of an automatic perforating machine for making sheet records for automatic player pianos. 11 is a blank record sheet in position to be moved and operated upon by this mechanism.

12 is a phonograph provided with a supporting member 13 for supporting a record element 15. This phonograph is arranged to be driven at a speed absolutely proportional to the speed at which the record sheet 11 of the piano is driven by being geared to a driving motor 16 supplied with power from any suitable source as 17 and controlled by formations 18 in the record sheet 110

11. The particular construction of this motor, and the character of the formations in the record sheet, and the manner in which they act to control the motor to cause it to drive the phonograph at a speed proportional to that of the record sheet, are all set forth in my co-pending application Serial No. 385,710, in which I describe a means for operating musical instruments in synchronism. By this arrangement the two record elements 11 and 15 may be driven at speeds absolutely proportional to each other at all times, and under normal running conditions the speed of the phonograph record is absolutely subject to the speed of the piano record element, the effect of the driving arrangement being entirely the same as that of a geared connection between the record elements.

20 In making the records, the record elements are driven at the proportional speeds by the apparatus just described. Preferably the phonograph has been placed on the other side of a partition 19 from the piano, or in 25 another room. The phonograph record is then made by accompanying the voice or other sound record to be made by the piano. By virtue of the phonograph being separated from the piano by partition 19, the 30 sounds of the piano are damped so that they have no effect upon the record element which is receiving the phonograph record. If the separation is not sufficient to dampen the sounds the accompaniment may be 35 played very softly. In some instances, it may be found advantageous to keep the phonograph in the same room with the piano, and suitably dampen the sounds by playing softly or by other means. If the performers who have acted to make the phonograph 40 record are skilful this record will have been made in perfect time. I next take this record and "fix" it, that is, make it a permanent record on the same record element or 45 another record element by any of the well known methods used in the art. Thereafter the record so made is replaced in the phonograph in the same room with the piano or perforating machine, the two record elements are again driven at the same proportional speeds, and the piano record is made 50 upon the blank sheet 11 by performing upon the piano or perforating machine in accompaniment with a reproduction of the phonograph record. The piano record sheet 11 is thus perforated in exact musical time with the phonograph record, and thereafter if the 55 two records are placed in a self-playing piano provided with an automatic phonograph attachment, such as that in my application referred to, the two records reproduce in accompaniment, giving the best and purest tones of the correct relative 60 prominence, and of exact musical time. 65 Moreover, the piano record having been

made in accompaniment of the phonograph record, the effect of the simultaneous reproduction is most harmonious and natural. In all voice records on the phonograph, when the two records are made in this manner, the piano record always follows the voice record in the most natural manner.

70 Not only is the method of my invention advantageous for the reasons specified, but it will now be evident that I may make the phonograph record in any of the methods now known to the art, instead of according to the first step of my method, and thereafter make the piano record by reproducing the phonograph record by arrangement giving the phonograph record a speed proportional to a blank piano record, and accompanying the reproduction by playing upon the perforator or other record making device, all as in accordance with the 80 85 third step of my method.

While I have described my invention in connection with a piano and phonograph, in which connection I find it most efficient at the present time, I desire to have it understood that my invention may be used in the making of the record elements of other instruments, and this whether the record elements are separate as described herein or connected in some manner as by being placed 90 upon the same sheet.

I desire to cover all modifications of my invention not falling without its generic spirit in the annexed claims.

What I claim is:—

1. The method of making a perforated music sheet to be used in accompaniment with a previously prepared phonograph record, which consists in reproducing on a phonograph the sounds represented by the phonograph record and simultaneously with such reproduction synchronously moving with said record a blank sheet in association with key-controlled punching instrumentalities, and then during such synchronized movement manipulating the controlling keys of the punching instrumentalities to cause the latter to produce in said sheet note perforations harmonizing in musical time, with the sounds reproduced from the phonograph record.
